DRAPERY MASTER CARRIER

Ellis I. Toder, 9225 Grace Lane,
Philadelphia, Pa. 19115

Filed Mar. 17, 1969, Ser. No. 16,271

Term of patent 14 years

Int. Cl. D8—03

U.S. Cl. D8—218

FIG. 1 is a perspective view from one side and below of my new design of drapery master carrier;

FIG. 2 is a bottom plan view of my new design of drapery master carrier;

FIG. 3 is a top plan view of my new design of drapery master carrier;

FIG. 4 is a side elevational view of my new design of drapery master carrier as would be seen when viewed along the line 4—4 of FIG. 3;

FIG. 5 is a side elevational view of my new design of drapery master carrier as would be seen when viewed along the line 5—5 of FIG. 3;

FIG. 6 is an end elevation of my new design of drapery master carrier as would be seen when viewed along the line 6—6 of FIG. 4;

FIG. 7 is an end elevation of my new design of drapery master carrier as would be seen when viewed along the line 7—7 of FIG. 4.

I claim:

The ornamental design for a drapery master carrier, as shown.
